(57) **CLAIM**

The ornamental design for a handle for a drawer, as shown and described.

DESCRIPTION

FIG. 1 is a front view of a handle for a drawer;
FIG. 2 is a top view of the handle for a drawer;
FIG. 3 is a bottom view of the handle for a drawer;
FIG. 4 is a front perspective view of the handle for a drawer;
FIG. 5 is a rear perspective view of the handle for a drawer;
FIG. 6 is a front perspective view of the handle for a drawer shown in environmental use;

FIG. 7 is a front perspective view of the handle for a drawer in an alternate position shown in environmental use; and,
FIG. 8 is a front perspective view of the handle for a drawer in an alternate position shown in a second environmental use.

The broken lines shown represent unclaimed subject matter and form no part of the claimed design.

1 Claim, 8 Drawing Sheets
